UNITED STATES PATENT OFFICE.

KENNETH W. NEVERS, OF ATHOL, MASSACHUSETTS.

ADJUSTABLE CURVE.

1,258,357.

Specification of Letters Patent.

Patented Mar. 5, 1918.

Application filed April 27, 1917. Serial No. 164,978.

To all whom it may concern:

Be it known that I, KENNETH W. NEVERS, a citizen of the United States, residing at Athol, in the county of Worcester and State 5 of Massachusetts, have invented certain new and useful Improvements in Adjustable Curves; and I do declare the following to be a full, clear, and exact description of the invention, such as will enable others skilled 10 in the art to which it appertains to make and use the same.

My invention has for its object to provide a simply constructed yet a highly efficient draftsman's curve which is adjustable 15 for drawing numerous curves which now require separate instruments, and with this general object in view, the invention resides in the novel construction to be hereinafter fully described and claimed, the descriptive 20 matter being supplemented by the accompanying drawing which forms a part of this specification and in which:

Figure 1 is a plan view;

Fig. 2 is an elevation of the front edge of 25 the device;

Fig. 3 is a longitudinal section on the plane of the line 3—3 of Fig. 1; and,

Fig. 4 is a detail horizontal section on the plane of the line 4—4 of Fig. 3.

30 In the drawings above briefly described the reference numerals 1 designate a pair of divergent arms which are substantially rigid although yieldable to a slight extent, said arms being joined at their inner ends 35 by a connecting portion 2 which forms therewith a bow, said portion having an opening through which an adjusting bolt 3 passes.

A flexible resilient and preferably gradu- 40 ated rule 4 extends between the ends of the arms 1 and is provided on its rear side with lugs 5 received between ears 6 formed on said arms, pivot pins 7 being passed

through said lugs and ears. The central portion of the rule 4 is reinforced by a leaf 45 spring 8 having longitudinal slots 9 in its ends through which studs 10 extend from the rule. It is to the center of the spring 8 that the adjusting bolt 3 is secured, said bolt having thereon a nut 11 abutting a 50 washer 12 bearing against the connecting portion 2 of the bow.

By constructing the device in the manner shown and described, adjustment of the nut 11 will spring the rule 4 a greater or 55 less amount to adjust the same for use in ruling straight lines or various curves. The invention is thus applicable for uses now requiring a great number of separate instruments.

60 Since probably the best results are obtained from the specific construction shown, this construction constitutes the preferred form of the device. I wish it understood, however, that within the scope of the invention as claimed, numerous minor changes 65 may be made without sacrificing the principal advantages.

I claim:—

A drawing instrument of the class de- 70 scribed comprising a bow, a flexible rule pivoted at its ends to the ends of said bow and having a pair of inwardly extending studs, a flat reinforcing spring contacting with the inner side of said rule and having 75 slots receiving said studs, and a screw-threaded adjusting device extending between the center of said spring and said bow.

In testimony whereof I have hereunto set 80 my hand in the presence of two subscribing witnesses.

KENNETH W. NEVERS.

Witnesses:

C. LESLIE MOULTON,
CHARLES W. FAULKNER.
